UNITED STATES PATENT OFFICE.

GARDNER KNAPP, OF SOMERVILLE, MASSACHUSETTS.

SUSPENSION-BRACKET.

SPECIFICATION forming part of Letters Patent No. 235,363, dated December 14, 1880.

Application filed September 10, 1880. (No model.)

To all whom it may concern:

Be it known that I, GARDNER KNAPP, a citizen of the United States, residing at Somerville, in the county of Middlesex and State 5 of Massachusetts, have invented certain new and useful Improvements in Suspension-Brackets; and I do hereby declare the following to be a full, clear, and exact description of the invention, such as will enable others skilled in 10 the art to which it appertains to make and use the same, reference being had to the accompanying drawings, and to letters or figures of reference marked thereon, which form a part of this specification.

15 This invention relates to improvements in spring-reels for suspending bird-cages, hanging pots, &c.; and it consists in the construction, arrangement, and combination of devices, as will hereinafter be more fully shown and 20 described, reference being had to the accompanying drawings, in which—

Figure 1 represents a front elevation with the cover of the apparatus shown as removed. Fig. 2 represents a rear view of the apparatus 25 with a portion of the case removed. Fig. 3 represents a vertical section on the line A B, shown in Fig. 1; and Fig. 4 represents a vertical section on the line C D, seen from x in Fig. 3.

30 Similar letters refer to similar parts wherever they occur on the different parts of the drawings.

a is the case or support of the reel; and a' is 35 the corresponding cover, between which parts the interior mechanism is preferably inclosed, although, if so desired, the cover a' may be entirely dispensed with and the form of the case or support a may be changed to a bar or bracket to be directly secured to a wall or ceiling with- 40 out departing from the main features of my invention.

a'' is a suitable loop, by means of which the reel-case or support for the mechanism can be suspended.

45 b is the stationary pivot, that is tightly driven into or otherwise firmly secured to the case or support a, as shown. Around said pivot b is loosely movable the spool or reel c, around which is wound the cord d, one end of which 50 is fastened to the said reel c, and having its outer end, d', projecting outside of the reel-

case, to allow the bird-cage or other object to be readily attached and suspended therefrom.

e is a coiled spring, one end of which is attached to the reel c, and the other end to the 55 stationary pivot b, for the purpose of automatically winding up the cord upon the said reel when the weight of the article suspended from the cord is gradually relieved, and this is the sole function of said spring, as it has 60 nothing to do whatever with sustaining the article suspended on the cord, which is accomplished by means of a frictional device arranged and constructed as follows:

To the face of the reel c, in an annular recess 65 thereof, is secured the ratchet-ring f, as shown. g is a pawl-plate having recesses, in which the pawls g' g' g' g' are loosely movable in and out from the center of said pawl-plate, the outer ends of which pawls engage into the 70 ratchet g when moved by their own gravity to their extreme positions, as shown by the lower and left-hand pawls in Fig. 4. On the face of the pawl-plate g is laid a washer, h, upon which rests a frictional spring-plate, i, as shown. 75

k is a screw that passes through the spring-plate i, washer h, and pawl-plate g, and is screwed into the stationary pivot b, as shown, by which arrangement a frictional resistance is obtained between the face of the pivot b and 80 the rear of the pawl-plate g when one or more of its pawls g' g' are locked to the ratchet-ring f, and tension is brought to bear on the cord or tape d, and on this frictional resistance I depend entirely for suspending the desired 85 bird-cage or other object, such frictional resistance being adjustable according to the weight of the suspended object by tightening or loosening the screw k.

It will be seen that one or more of the pawls 90 g' g' are automatically locked to the ratchet-ring f as long as the cord or tape d is kept taut by the suspended object, which is thus held by the friction between the pawl-plate g and stationary pivot b; but as soon as the ten- 95 sion on the cord or tape d is gradually relieved, as may be occasioned by gently raising the suspended object, the spring e acts on the reel c to turn it around to wind up the slack of the cord or tape d, during which motion of the 100 reel its ratchet-ring f passes freely by the tapering or inclined ends of the pawls g' g'.

To prevent the cord or tape *d* from flying up and winding too quickly on the reel *c*, in case the object suspended should be instantaneously removed or the cord or tape *d* be accidentally broken, I employ a pawl, *l*, hinged to the said reel *c*, in combination with a notch-pin or recess, *l'*, in the upper part of the case, as shown in Figs. 3 and 4, by which arrangement the said pawl *l* is caused to lock automatically into its notch or pin *l'* by the centrifugal force acting on the free end of said pawl, when the reel *c* is quickly rotated in the manner above described. When the object suspended is gently raised or lowered the said locking-pawl will rest within its recess *c'* on the reel *c*; but when the reel is quickly liberated the centrifugal force will throw out the pawl *l*, which will be locked into the recess or pin *l'* as soon as the said pawl reaches its upper position, as shown in Fig. 4, and conse-

quently the reel *c* cannot be accidentally wound up more than one revolution.

I claim—

1. In combination, the case *a*, stationary pivot *b*, reel *c*, cord or tape *d*, spring *e*, ratchet *f*, pawl-plate *g*, pawls *g' g' g' g'*, spring-plate *i*, and adjustable screw *k*, as and for the purpose described.
2. In combination, the case *a*, stationary pivot *b*, reel *c*, cord or tape *d*, spring *e*, ratchet *f*, pawl-plate *g*, pawls *g' g' g' g'*, spring-plate *i*, adjustable screw *k*, locking-pawl *l*, with its notch-pin or recess *l'*, as and for the purpose set forth and described.

In testimony whereof I have affixed my signature in presence of two witnesses.

GARDNER KNAPP.
